UNITED STATES PATENT OFFICE.

SILAS R. DIVINE, OF LOCH SHELDRAKE, NEW YORK, ASSIGNOR TO THE
REND ROCK POWDER COMPANY, OF NEW JERSEY.

COMPOSITION FOR PREPARING EXPLOSIVE COMPOUNDS.

SPECIFICATION forming part of Letters Patent No. 289,765, dated December 4, 1883.

Application filed August 7, 1883. (No specimens.)

To all whom it may concern:

Be it known that I, SILAS R. DIVINE, of Loch Sheldrake, Sullivan county, State of New York, and a citizen of the United States, have 5 invented an Improved Composition of Matter for Use in Preparing Explosive Compounds, of which the following is a full, clear, and exact specification.

The object of my present invention is to facilitate the explosion by the use of sulphur of an explosive compound composed of two ingredients, the one a solid—such as crushed or powdered chlorate of potash—and the other a liquid—such as “dead-oil”—which ingredients are united by permitting the solid to absorb the liquid, and to effect the incorporation of the sulphur with the mass of the combined ingredients at the same time that the uniting of the said ingredients in their exact proper 15 relative proportions in the explosive is accomplished, and wholly without the exercise of skill on the part of the workman performing the act.

My invention consists in a composition of matter not in itself explosive, which is a fluid mixture composed of the liquid ingredient of the explosive—such as dead-oil—and a volatile fluid—such as bisulphide of carbon—and sulphur, in a finely-powdered state, dissolved 20 in said volatile fluid.

In composing my mixture I take the quantity of the liquid ingredient of the explosive, which is the proper proportion thereof relatively to the solid ingredient, and which, in the case of dead-oil, is about one part thereof to seven and one-half parts of chlorate of potash, and to this I add such a quantity of the bisulphide of carbon or other volatile fluid in which the sulphur has been dissolved as will 25 make a fluid-volume equal to the total fluid-absorbing capacity of the solid ingredient of the compound; and as the total fluid-absorbing capacity of the chlorate of potash is about double the volume of the quantity of dead-oil, which constitutes the proper relative proportion thereof in the explosive, I add to the dead-oil, when it is used, about an equal volume of the bisulphide of carbon. Sulphur, preferably in a finely-powdered state, is dissolved 30

in the bisulphide of carbon, and the desirable 50 proportion of sulphur is from about one to three per cent. thereof relatively to the mass of the combined solid and liquid ingredients of the explosive.

It is evident that other fluid hydrocarbons 55 which are practically non-volatile in a free state at ordinary temperatures or nitro-compounds—such as nitro-benzole—may be employed, wholly or in part, as constituents of my mixture, when their use as the liquid ingredient of the explosive is desired; and also that other volatile fluids in which sulphur will 60 dissolve than bisulphide of carbon may be employed in the mixture.

It is my purpose and intention to make this 65 mixture of the liquid ingredient of the explosive—such as dead-oil—and the volatile fluid and sulphur in solution, and to put up the same in vessels or cans suitable for transportation, and to supply it in this way to the consumer. Its use by the consumer is intended 70 to do away with the necessity for the employment of skilled labor in effecting the final combining of the ingredients of the explosive. The workman simply soaks the solid ingredient—such as chlorate of potash—in this mixture until saturation is effected, and then lays 75 the saturated mass in the open air or other convenient place for a short time, when the volatile fluid evaporates and escapes, leaving 80 the sulphur incorporated with the wet or moist mass of the combined chlorate of potash and dead-oil at the same time that the exact proper proportions in the compound of said solid and liquid ingredients are secured. An explosive is 85 thus constituted which may be used in blasting loose or “rotten” rock or shale or earth.

The explosive compound thus produced and the process by which the exact proportions of the ingredients of the compound are at all 90 times secured I have made subjects of separate applications for Letters Patent; and hence I do not claim them here, but limit my claim hereunder to the described composition of matter, which is a mixture in the proportions indicated of the liquid ingredient of the explosive—such as dead-oil—a volatile fluid—such as bisulphide of carbon—and sulphur in so-

lution in the latter, for the specific purpose set forth.

What I claim as my invention, and desire to secure by Letters Patent, is—

5 The composition of matter herein described, which consists in a fluid mixture of the liquid ingredient of the explosive—as dead oil—the volatile fluid—as bisulphide of carbon—and

sulphur in solution in the latter, substantially in the proportions and as and for the purpose so specified.

SILAS R. DIVINE.
